ABSTRACT OF THE DISCLOSURE

A sandal adapted to accommodate a foot encased in a surgical cast. The sandal is of non-bendable construction and is formed by a generally rectangular platform of high-density foam plastic which is laminated to an underlayer of relatively rigid tread material. The forepart of the platform, from a transverse line lying below the ball of the foot and extending to the front edge, is of diminishing thickness to define a wedge facilitating a rocking motion. Interposed between the platform and the tread is a fabric piece having complementary flaps extending from opposite sides of the sandal, the flaps being contoured to define the vamp portion and the ankle cuff portion of a full shoe when the flaps are tied together against the cast.

BACKGROUND OF INVENTION

This invention relates generally to sandals or clogs, and more particularly to a non-bendable sandal adapted to accommodate a left or right foot encased in a surgical cast.

In order to immobilize a fractured or broken foot, it is the usual practice to encase the foot in a surgical cast which extends well above the ankle and takes the form of a rigid dressing made from gauze impregnated with plaster of Paris. Such casts, although somewhat fragile, are relatively heavy and cumbersome. However, in most instances, one having a foot in a cast is still capable of walking. In fact, some exercise is desirable to stimulate circulation and promote the healing process.

It is not ordinarily possible to step directly on a cast. The usual practice therefore is to walk with the assistance of a crutch so that the encased foot is not brought down on the ground. This makes walking very difficult. Moreover, the cast remains unprotected, and should one inadvertently take a step with it, the cast will be soiled and possibly damaged.

While it may be possible to place an oversize shoe over the cast, this is not advisable, for conventional shoes are relatively flexible, whereas foot casts are inflexible, so that the shoe would not protect the cast. On the other hand, should one use wood clogs for this purpose, the total absence of cushioning characteristic of such clogs would make walking on an injured foot difficult.

BRIEF DESCRIPTION OF INVENTION

Accordingly, it is the main object of this invention to provide a sandal which is attachable to a cast-encased foot, the sandal protecting the cast while facilitating walking.

More specifically, it is an object of the invention to provide a non-bendable "walker" sandal of the above type whose configuration is such that the sandal is capable of a rocking motion, thereby making walking possible despite the non-bendable character of the cast. This rocking motion may be of the heel or ball type or a combination thereof.

Yet another object of the invention is to provide an inexpensive sandal having contoured flaps which are laceable, making it possible to quickly and firmly attach the sandal to surgical casts of different size.

Also an object of the invention is to provide a sandal of the above type which may be used as a post-surgical

2

shoe without a cast or as a "rester" shoe which may be worn on any painful foot.

Briefly stated, these objects are accomplished in a sandal of effectively non-bendable construction formed of a generally rectangular platform of high-density foam plastic laminated to an underlayer of tread material. The forepart of the platform, from a transverse line underlying the ball of the foot and extending to the front edge, is of diminishing thickness to define a wedge. This facilitates a rocking action when the weight of the encased foot is brought to bear on the sandal. A similar wedge may be provided on the heel of the platform.

Interposed between the tread and platform and laminated thereto is a fabric piece having two complementary flaps extending from opposite sides of the sandal, the contours of the flaps being such that when placed against the cast and laced together, the flaps define the vamp and ankle portions of a full shoe.

BRIEF DESCRIPTION OF DRAWING

For a better understanding of the invention as well as other objects and further features thereof, reference is made to the following detailed description to be read in conjunction with the accompanying drawing, wherein:

FIG. 1 is a perspective view of a foot encased in a surgical cast and having a sandal in accordance with the invention bound thereto;

FIG. 2 shows the sandal removed from the cast, with the flaps of the sandal outstretched;

FIG. 3 is a side elevation of the sandal bound to the cast;

FIG. 4 is a transverse section take in the plane indicated by line 4—4 in FIG. 3; and

FIG. 5 is a perspective view of a sandal similar to that of FIG. 1, but in boot size going above the ankle.

DESCRIPTION OF INVENTION

Referring now to FIG. 1, there is shown an injured foot 10 which is encased in a rigid plaster-of-Paris cast 11. The coverage of the cast is such as to expose the extremity of the heel and the leading portion of the toes, the cast otherwise extending well up the leg to immobilize the injured foot. Attached to the encased foot is a sandal in accordance with the invention and generally designated by numeral 12.

The sandal is constituted by a platform 13, formed of high-density foam plastic material such as polyethylene or vinyl foam, having a slight degree of resilience to provide some measure of cushioning and springness. The platform is generally rectangular in form, with a squared-off rear edge 13A and a squared-off front edge 13B, the corners at the front edge being chamfered to impart a clog-like appearance to the sandal.

The thickness of platform 13, as been seen in FIG. 2, is uniform throughout, except that from a transverse line X underlying the ball of the foot and extending to the front edge 13B, the thickness diminishes progressively to provide a wedge formation. In walking, the weight of the foot is brought to bear on the platform and because of the wedge formation, this causes a rocking motion at the ball of the foot. Such motion facilitates movement without bending of the sandal and without imposing stresses on the encased foot. A similar wedge formation may be provided at the heel of the sandal.

Laminated by a suitable cement or adhesive to the underside of platform 13 is a layer 14 of relatively rigid tread material which may be formed of hard rubber having a good wearing surface which is ribbed to improve traction. The exposed face of platform 13 is planar to receive the plantar area of the foot cast. The weight of the encased foot bears down on platform 14 which provides cushioning to minimize shock, but the laminated

platform and tread combination, when secured to the cast, is relatively inflexible and resists bending action in the course of walking.

Interposed between platform 13 and tread 14 is a fabric piece 15, preferably made of canvas, the edges of the piece being reinforced with a bead. The piece is provided with two complementary flaps 15A and 15B which extend from opposite sides of the sandal and which, when brought up against the cast, define the vamp portion and ankle cuff portion of a full shoe. The vamp portion 10 margins of the flaps are provided with rows of eyelets 16 for receiving lacing 17 and the ankle cuff portion margins are provided with rows of eyelets 18 for receiving lacing 19. When the flaps are laced together, the sandal is firmly secured to the encased foot and the wearer is then able to walk with reasonable comfort. But because the attached sandal is unbendable, only a rocking motion is permitted about the wedge portion at the ball of the foot. Should a wedge also be provided at the heel of the sandal (not shown), one may rock both heel and ball. 15

While laces have been shown as the means to hold the flaps to the cast, other known means may be used for this purpose, such as a Velcro fastener or strap and buckle arrangements.

The sandal is also useable as a post-surgical shoe without a cast, in which case one may turn down the cuff and use the sandal in the form of a half shoe. But when used as a "walker" for a foot in a cast, it is important to keep the ankle cuff turned up to prevent any relative motion between the cast and sandal. The sandal may also be worn, cuff up or down, as a "rester" shoe on any painful foot. 20

While there have been shown and described preferred embodiments of the invention, it will be appreciated that many changes and modifications may be made therein without, however, departing from the essential spirit of the invention.

I claim:

1. A non-bendable sandal adapted to accommodate a foot encased in a surgical cast, said sandal comprising:

- (A) a generally rectangular platform formed of foam plastic material, the forepart of the platform being of diminishing thickness from a transverse line underlying the ball of the foot and extending to the front edge to define a wedge facilitating a rocking motion, the upper surface of the platform being planar to receive the plantar area of the cast,
- (B) a relatively stiff tread layer laminated to the underside of the platform,
- (C) a contoured piece interposed between the platform and layer and laminated thereto, said piece having complementary flaps extending from opposite sides of the sandal, said flaps, when brought together against the cast, defining the vamp portion and ankle cuff portion of a full shoe, and
- (D) means to connect the flaps to each other to secure the sandal to the cast.

2. A sandal as set forth in claim 1, wherein said platform is formed of high-density polyethylene foam having a slight resilience.

3. A sandal as set forth in claim 1, wherein said tread layer is formed of hard rubber which is ribbed.

4. A sandal as set forth in claim 1, wherein said means are constituted by laces.

5. A sandal as set forth in claim 1, wherein said piece is formed by canvas.

6. A sandal as set forth in claim 1, wherein the heel portion of the platform is of diminishing thickness to define a wedge facilitating a rocking motion.
